UNITED STATES PATENT OFFICE.

JOHN T. DALCHER, OF BAYONNE, NEW JERSEY.

HEADER FOR BOILERS.

Application filed May 12, 1925. Serial No. 29,754.

This invention relates to headers for boilers and has for its object the provision of means for securing the covers to the hand holes therein.

5 This object is attained by the mechanism illustrated in the accompanying drawings.

For the purpose of illustrating the invention, one preferred form thereof is illustrated in the drawings, this form having been found 10 to give satisfactory and reliable results, although it is to be understood that the various instrumentalities of which the invention consists can be variously arranged and organized, and the invention is not limited to the 15 precise arrangement and organization of these instrumentalities as herein shown and described except as required by the scope of the appended claims.

Of the drawings:

20 Figure 1 represents a front elevation of a header without covers on the hand holes.

Figure 2 represents a side elevation of same, showing covers for hand holes and with the lower end in section.

25 Figure 3 represents a front elevation of a portion of a header drawn to an enlarged scale and showing the hand hole cover and holding device therefor.

Figure 4 represents a horizontal section of 30 the same on line 4, 4, on Fig. 3, and

Figure 5 represents a side elevation of a portion of the same.

Similar characters indicate like parts throughout the several figures of the drawings.

35 In the drawings 10 is a sectional header such as is used in certain types of steam boilers.

This header is preferably sinuous as shown, 40 but obviously may have straight side walls if desired.

These headers must be provided with hand holes 11 to give access to the boiler tubes 12 which are secured to and extend from the rear 45 wall of said headers as is usual in such constructions of boilers.

The hand holes 11 have usually been made oval and the covers for closing the same have been inserted through these holes and positioned against the inner face of the front wall 50 of the header.

To accomplish this the hand holes are necessarily made quite large and weaken the header and one aim of the present invention

is to greatly reduce the area of the hand holes, 55 thereby greatly strengthening the headers.

These covers when inserted through the hand holes either must have gaskets interposed between flanges on said covers and the inner wall of the header or must be formed 60 with a ground face fitted to a ground face at the inner end of the hand hole.

Both of these methods are objectionable on account of the expense incurred in such constructions.

65 To obviate the difficulties found to exist in the constructions now in general use, I form the hand holes 11 cylindrical with a slight inclination to the wall thereof, said hole having a less diameter at the rear end than at 70 the forward end thereof.

The holes 11 thus made may be of a diameter only slightly in excess of that of the boiler tubes 12.

75 The cover 13 for said hand hole 11 is made with a cylindrical wall 14 adapted to fit into said hand hole and its inner end is semi-spherical or cup-shaped as indicated at 15.

The header 10 is provided on opposite sides of each hand hole 11 with lugs or projections 16 having hook members 17 formed thereon, each hook member 17 having a stop shoulder 18 formed integral therewith.

These hook members 17 extend in opposite directions, as for instance, all those on the 85 left of the header extend upwardly, while all those on the right extend downwardly.

The hook members 17 are provided as supports for the cross bar 19, the opposite ends which are positioned therein.

90 The cross bar 19 has threaded thereto midway of its length a screw 20 having a head 21 at its outer end by which said screw may be adjusted relatively to the bar 19.

The opposite end impinges against the center of the outer face of the disk portion of the cover 13 and by adjusting the screw 20 said cover may be forced into the hand hole 11 so that an absolutely tight joint is made between the inclined wall of said hole and the 100 cover 13.

The cover 13 is provided at its outer end with oppositely disposed outwardly extending flanges 22 which provide means for removing the said cover from the hand hole 11.

105 When the cover 13 is first inserted into the hand hole 11, there is sufficient room for the bar 19 to be inserted under the hooks 17, but

when the screw 20 is rotated to force the cover 13 further into the hole 11, the bar 19 will be moved outward until its outer face bears on the face 23 of the hooks 17.

5 When in this position the shoulders 18 prevent the bar 19 from rotating about the axis of the screw 20 and thereby becoming displaced from said hooks 17.

It is obvious that in this construction the 10 hand hole cover 13, with its holding members 19, 20, are always outside the header and in plain view making them readily accessible in case it is desired to remove a cover.

By such a construction as is herein shown 15 and described any cover may be quickly removed and replaced without interfering with any of the other covers.

The entire cover is formed of pressed steel with a large fillet 24 at the junction of the 20 inner disk portion 15 and the cylindrical wall 14, said wall having a slight taper fitting a corresponding taper on the wall of the hole 11.

As a consequence a small pressure obtained 25 by rotating the screw 20 will cause the cover 13 to make an intimate contact with the bore of the hole 11, thus forming an absolutely tight metal to metal joint and avoiding the use of all gaskets.

30 Owing to the semi-spherical concavity 15 in the inner end or disk portion of the cover 13, any additional pressure applied to said cover 13 through said screw 20 will tend to increase the diameter of the cover and thus 35 increase the pressure of contact between the wall 14 and the bore of the hand hole 11.

In case there should be a slight deviation 40 between the bore of the hole 11 and the wall 14 of the cover 13, the force applied by the screw 20 will tend to squeeze the metal of the cover into any existing imperfections or crevices of the bore and assure a perfect metal to metal contact even under such conditions.

Even if the body of the header should 45 warp slightly, due to the internal stresses when heat is applied, thus causing the bore of the hand hole to be out of round, the cover 13 is flexible enough so that when sufficient force is applied by means of screw 20, 50 a metal to metal contact around the whole circumference of the cover can be obtained.

By utilizing this construction of hand hole 55 covers, the area of the hand hole may be reduced 16% for four inch tubes and 20% for three inch tubes.

This greatly increases the strength of the headers.

The tubes 12 are inclined relatively to the 60 header 10 as indicated in Fig. 2 and consequently the front and rear walls of the header are provided with a plurality of parallel flat faces 25, 26 which are in echelon as shown in Fig. 2.

This construction makes it possible for the 65 rear faces 26 to be perpendicular to the axes

of the tubes 12 and the hand holes 11 to be aligned with the holes in the rear wall of the header.

It is believed that the operation and many advantages of the invention will be understood 70 without further description.

Having thus described my invention, I claim:

1. A hollow header for boilers having in the outer wall thereof a cylindrical hand 75 hole of which the cylindrical wall is unbroken, said header being provided with outwardly extending hooked members on opposite sides of said hole; a cover having an unbroken peripheral surface insertable into and fitting said hand hole; a cross bar positioned by said hooked members free from contact with said cover; and means on said cross bar for retaining said cover in position.

2. A hollow header for boilers having in the outer wall thereof a cylindrical hand 80 hole of which the cylindrical wall is unbroken; a bar secured to said header by hooked projections extending outwardly from the front wall of said header and extending across said hole; a cover having an unbroken peripheral surface insertable into and fitting said hole; and a screw threaded to said bar for retaining said cover in position and locking said bar to said projection of said header.

3. A hollow header for boilers having in the outer wall thereof a hand hole with a tapered bore of which the surface is unbroken; a cover having a conical unbroken 100 peripheral surface fitted into said hole; a bar extending across said hole and removably positioned on said header; and means adjustably mounted on said bar for forcing said cover into said hole with the periphery 105 of said cover in tight contact with the wall of said hand hole.

4. A hollow header for boilers having in the outer wall thereof a hand hole with a tapered bore of which the wall is unbroken; 110 a cover having a conical unbroken peripheral surface fitted into said hole and having its inner end cupped outwardly; a bar extending across said hole and positioned on said header; and means adjustably mounted on said bar coacting with the cupped portion of said cover for forcing said cover into said hole and spreading the inner end of said cover into tight contact with the wall of said hole.

5. A hollow header for boilers having in the outer wall thereof a hand hole with a tapered bore of which the surface of the wall is unbroken; a cover having a conical unbroken peripheral surface fitted into said 125 hole and provided on its outer end with laterally extending removing means spaced from the outer face of said outer wall; a bar extending diametrically across said hole and positioned on said header free from contact 130

with said cover; and means adjustably mounted on said bar for forcing said cover into said hole with the periphery of said cover and in tight contact with the wall of said hand hole.

6. A hollow header for boilers having in the outer wall thereof a tapered hand hole of which the wall is cylindrical and unbroken; a cover insertable into said hole and provided with an unbroken cone-shaped peripheral surface adapted to contact with the wall of said hole; and means removably mounted on and free from contact with the outer face of said header for forcing said cover into said hole and the inclined peripheral surface of said cover into close contact with the wall of said hand hole.

7. A hollow header for boilers having in the outer wall thereof a tapered hand hole of which the wall is cylindrical and has an unbroken surface; a cover insertable into said hole and provided with a cone-shaped peripheral surface adapted to contact with the wall of said hole and having its inner end cupped outwardly; and means supported on the outer face of said header engaging the outwardly cupped end of said cover and adjustable to force said cover into said hole and spread the inner end of said cover into tight contact with the wall of said hole.

8. A hollow header for boilers having in the outer wall thereof a tapered hand hole of which the surrounding wall has an unbroken surface; a cover insertable into said hole and provided with a cone-shaped peripheral surface adapted to contact with the wall of said hole; oppositely disposed members integral with said header extending from the outer face thereof and having hooks thereon extending in opposite directions; a bar extending diametrically across said hole and positioned by said hooks free from contact with said cover; and a screw threaded to said bar and impinging on the center of said cover adapted to simultaneously force said bar against said hooks and seat said cover in said hand hole.

9. A hollow header for boilers having in the outer wall thereof a tapered hand hole of which the surrounding wall is cylindrical and has an unbroken surface; a cover insertable into said hole and provided with a cone-shaped peripheral surface adapted to contact with the wall of said hole; oppositely disposed members extending outwardly from

the outer face of said header and having hooks thereon extending in opposite directions, said hooks having stop shoulders at their outer ends; a bar extending diametrically across said hole and positioned by said hooks free from contact with said cover; and a screw threaded to said bar and impinging on the center of said cover adapted to simultaneously force said bar against said hooks and seat said cover in said hand hole.

10. A hollow header for boilers having in the outer wall thereof a tapered hand hole of which the surface of the surrounding wall is unbroken; a cup-shaped cover having a tapered cylindrical portion extending beyond the outer face of said header, the peripheral surface of said cylindrical portion being unbroken and fitting said hole; removable means on said header for forcing said cover into said hole with said cylindrical portion in tight contact with the wall of said hole; and oppositely disposed flanges extending laterally from the outer end of said cylindrical portion parallel to the outer wall of said header and free from contact therewith.

11. A hollow header for boilers having a plurality of parallel flat faces in the front and rear walls thereof with a hole in each rear face to receive a boiler tube and a slightly larger hand hole in each front wall aligned with said rear hole, said hand hole having an unbroken tapered wall; a tapered cover insertable into and tightly fitting each hand hole, the peripheral surface of said cover being unbroken; and adjustable means supported on the front face of said header for forcing said cover into said hand hole and retaining it in position therein.

12. A hollow header for boilers having a plurality of parallel flat faces in the front and rear walls thereof with a hole in each rear face to receive a boiler tube and a slightly larger hand hole in each front wall aligned with said rear hole, said front and rear faces both being in echelon; a tapered cover insertable into and tightly fitting each hand hole, the peripheral surface of said cover being unbroken; and means removably supported on each front wall for forcing said cover into said hand hole and retaining it in position therein.

Signed by me at Bayonne, N. J., this 8th day of May, 1925.

JOHN T. DALCHER.
